MARTIN L. HUNKER, OF WHEELING, WEST VIRGINIA, ASSIGNEE TO WHITAKER-
GLESSNER COMPANY, A CORPORATION OF WEST VIRGINIA.

METHOD OF PRODUCING EAVES-TROUGHS.

1,377,251.

Specification of Letters Patent. Patented May 10, 1921.

Application filed June 21, 1920. Serial No. 390,401.

To all whom it may concern:

Be it known that I, MARTIN L. HUNKER, a citizen of the United States of America, and resident of Wheeling, county of Ohio, 5 and State of West Virginia, have invented certain new and useful Improvements in Methods of Producing Eaves-Troughs, of which the following is a specification.

This invention relates to the manufacture 10 of eaves troughs and other sheet metal products of arcuate cross-sectional form, and it has for its object to provide an improved method or process of producing eaves troughs and the like whereby the metal is 15 gradually drawn or developed in a succession of operations into an accurately curved trough shape, forming a product which is devoid of the distortions and irregularities appearing in such troughs as produced by 20 methods heretofore prevailing.

Hitherto, in the production of eaves troughs, it has been the universal practice to shape the body of the trough by a succession of pressing or rolling operations 25 during which the lateral edges of the blank, or the lateral rolls or beads where such were carried by the blank, have been rigidly held and in which the entire body of the blank, or that portion of the latter between the 30 beads, has been at each successive operation received between and tightly gripped by the coöperating forming dies or rolls. Due to the fact that, in practising such method, the lateral edges or beads are held rigidly and 35 that the upper and lower dies or rolls seat in coöperative relation to the blank throughout the entire opposite surfaces of the latter from the first to the last of the successive trough-forming operations, as aforesaid, the 40 metal of the blank is so confined that free and even distribution or "flow" thereof during the successive operations is absolutely prevented, resulting in the production of a trough which presents edges or beads having 45 an irregular undulatory, or wavy, form.

Various expedients having for their purpose to obviate or remedy this defect have been resorted to, as, for instance, the provision of crimps, corrugations, angles and 50 like edge-stiffening formations in the edges of the trough.

By means of the method which constitutes the subject-matter of the present invention

I am enabled to produce a trough having an 55 accurately regular curvature and having

perfectly straight, or non-sinuous, edges or beads.

In carrying out my invention, following the formation of the lateral beads, where the trough is to have such beads, the blank 60 is advanced successively between coöperating forming dies which are arranged in a plurality of sets and which are preferably of the rotary type, although reciprocating dies may also be employed for the purpose. 65 In order that the metal of the blank shall be afforded the greatest possible freedom to adjust itself to the progressively increasing distortion produced in the development of the trough shape, the development is made 70 to begin at a point remote from, or midway between, the edges of the blank and thence to proceed progressively in opposite directions to or adjacent to said edges, and the blank is at no time subjected to restraint 75 at points lateral with respect to the median line in which the successive dies act to produce the requisite successive bends. Otherwise expressed, the sets of dies employed operate successively in areas of progressively 80 increasing width and each confines against or restrains from free and unobstructed accommodating movement only the area upon which it directly operates.

Another important feature of my invention, and one to which especial attention is directed, consists in producing, as an initial step in the development of the trough, preliminary trough-shaping curves at points, or in areas, contiguous to the lateral edges 90 of the blank, such curves being designed to coincide with the curves produced in the final operation and facilitating the production of a trough having perfect uniformity 95 of curvature. This preliminary shaping is especially important, if not positively essential, to the production of eaves troughs having lateral beads, it being practically impossible to produce at a final step in the forming operations the proper curvature 100 directly contiguous to the bead without subjecting such bead to distortion.

The accompanying drawings, Figures 1 to 22, inclusive, illustrate the successive shapes imparted to the metal blank in following 105 the different steps of my process for the development of a trough.

As herein illustrated, it is designed that the finished product, depicted in Fig. 22, shall be an eaves trough the body 1 of which 110

has rolls or beads 2 provided with the usual angular flanges, or inner locks, 3; and while the description which follows contemplates the formation of a bead on each of the lateral edges of the trough, it will be understood that one of said beads may be omitted, as when a plain edge is desired.

A preferred form of mechanism or apparatus for performing the steps of my process 10 is shown in a companion application, Serial No. 390,402, but it will be understood that the process may be carried out by other mechanisms or instrumentalities than the dies of roller type shown in said application.

15 The process involves three major operations performed in sequence as follows: First, the formation of marginal flanges disposed at right angles to the plane of the intermediate body portion of the blank.

20 Second, the curling of said marginal flanges to form lateral rolls or beads. Third, the bending of the beaded body into arcuately curved trough shape. Further, each of said major operations involves a succession 25 of relatively graduated minor operations which constitute steps in which the blank, or portions thereof, are progressively drawn or developed to produce the requisite shape.

The first operation performed on the plain 30 sheet is the formation of downturned right-angle terminal flanges 4 along the lateral edges of the sheet, as shown in Fig. 1, said flanges being of narrow width and designed without further shaping to constitute the 35 inner locks 3 of the finished product. The second operation consists in producing bends 5 in the blank at points located inward an appropriate distance from the terminal flanges 4 for forming marginal flange por-

40 tions 6 having very slight downward inclinations, and, at the same time, it consists in forcing the body, or that portion of the blank which lies between said bends 5, downward into the form shown in Fig. 2, 45 which form is then preserved or maintained throughout the various successive steps constituting the terminal-flange bending and the bead-forming operations. This slight downward bending of the body produces

50 contiguous to each bend 5 a gradual curvature, indicated at 7, which is preserved throughout and appears in the finished product. Following said second operation, the marginal flanges 6 are acted upon in a succession of graduated operations for progressively increasing their angles of inclination, as shown in Figs. 3 to 7, inclusive, until they are finally disposed at right angles to the original plane.

60 The blank is next subjected to a series of relatively graduated operations in which the marginal flanges 6 are progressively curled, as shown in Figs. 8 to 16, inclusive, for producing the lateral rolls or beads 2 to be 65 borne by the finished product.

The blank is next subjected to the shaping action of a series of dies which operate to develop the blank body 8, or that portion located between the previously produced curves 7, from the approximately plane form 70 shown in Figs. 2 to 16, inclusive, to the final semi-circular trough-shape shown in Fig. 22. This final development is accomplished 75 gradually, and, in accordance with the present invention, involves the employment of a series of sets of coöperating dies which successively operate upon the blank body in areas of progressively increasing width and each of which acts to grip only so much 80 of the area of said body as it directly operates upon, leaving the remainder of the body free to adjust or accomodate itself to the stresses imposed upon or set up within the blank. While the lower, or female, dies of the trough-shaping series should conform 85 to and substantially correspond in width with that of the blank which is passed thereover, each of the upper, or male, dies has a width no greater than is necessary to produce the depression of the metal to the extent 90 desired. The blank body is initially acted upon by an upper die of extremely narrow width which produces a central longitudinal downwardly-pressed angular bend indicated 95 at 9 in Fig. 17. Each succeeding upper die of the series is of relatively increased width and acts to depress the central portion of the blank body to a greater depth, so that the regular semi-circular form is approached gradually and progresses from the center or 100 median line outwardly until the curvature produced by the last set of the series accurately merges or meets in accord with the previously produced curves 7.

Due to the provision of the curves 7 at an 105 initial operation in the development of the blank, it is rendered possible to produce contiguous to the beads the degree of curvature which is required to round out the trough into a uniformly curved semi-circular form and which, because of the resiliency of the metal of the blank, is not obtainable by the use of shaping dies in a final operation.

It will be particularly noted that the development of the final trough shape is performed by dies or rolls the peripheral or metal-shaping surfaces of which are produced on radii of progressively increasing 110 length. Owing to the fact that the metal 115 of the blank is acted upon first along its center line producing a curvature of small radius and is thence gradually developed by produced curvatures of progressively increasing radii, the natural tendency of the lateral portions of the metal is to spring inward, and not outward as is the case when the curvature is developed by heretofore prevailing methods. The result is that material of a resilient character is readily de- 120 125 130

veloped into true semi-circular shape which has heretofore been possible only where the material employed is of a particularly soft or non-resilient character.

5. What is claimed is—

1. The method of forming eaves troughs, which includes bending the stock into trough shape by a succession of curving operations in which it is progressively developed from 10 its center outward in opposite directions in areas of relatively increasing width and in which areas lateral to that acted upon are unconfined.

2. The method of forming eaves troughs, 15 which includes bending the stock into trough shape by a succession of curving operations in which it is initially engaged and bent along its center line in an area of small width and is then subjected to a series of 20 complementary bends in areas of progressively increasing width and in which areas lateral to that acted upon are unconfined.

3. The method of forming eaves troughs, 25 which includes the formation of lateral beads on a sheet metal blank, depressing the body of the blank at an initial step in the bead-forming operations to form curves contiguous to the subsequently formed beads, and finally bending said body into 30 trough shape by a succession of curving operations in which it is progressively developed from its center outward in opposite directions in areas of relatively increasing width.

35. 4. The method of forming eaves troughs, which includes the formation of lateral beads on a sheet metal blank, depressing the body of the blank at an initial step in the bead-forming operations to form curves 40 contiguous to the subsequently formed beads, and finally bending said body into trough shape by a succession of curving operations in which it is progressively developed from its center outward in opposite 45 directions in areas of relatively increasing width until the curvature produced meets and is supplemented by the initially formed curves.

5. The method of forming eaves troughs, 50 which includes the formation of lateral beads on a sheet metal blank, depressing the body of the blank at an initial step in the bead-forming operations to form curves contiguous to the subsequently formed beads, 55 and finally bending said body into trough shape by a succession of curving operations in which it is progressively developed from its center outward in opposite directions in areas of relatively increasing width while 60 the portions of the blank located laterally of the areas acted upon remain unconfined.

6. The method of forming eaves troughs, 65 which includes the formation of lateral beads on a sheet metal blank, depressing the body of the blank at an initial step in the

bead-forming operations to form curves contiguous to the subsequently formed beads, and finally bending said body into trough shape by a succession of curving operations in which it is progressively developed from its center outward in opposite directions in areas of relatively increasing width until the curvature produced meets and is supplemented by the initially formed curves, the portions of the blank located laterally of the areas acted upon in the development of the body being unconfined and free to accommodate themselves to the strains imposed. 70

7. The method of forming eaves troughs, 80 which includes the formation of lateral beads on a sheet metal blank, depressing the body of the blank at an initial step in the bead-forming operations to form curves contiguous to the subsequently formed beads, 85 and finally bending said body into trough shape by means of a series of successively operating sets of dies which act to develop said body from its center outward in opposite directions in areas of progressively increasing width, the blank being confined against self-adjusting movement only in areas directly operated upon by said dies for forming bends. 90

8. The method of forming eaves troughs, 95 which includes the formation of lateral beads on a sheet metal blank, depressing the body of the blank at an initial step in the bead-forming operations to form curves contiguous to the subsequently formed beads, 100 and finally bending said body into trough shape by means of a series of successively operating sets of dies the metal shaping surfaces of which have radii of progressively increasing length. 105

9. The method of forming eaves troughs, which includes bending a sheet metal blank into trough shape by a series of successive operations in which it is initially acted upon along its median line by a die having a 110 narrow blank-engaging surface and is then gradually developed by a succession of dies having blank-engaging surfaces of progressively increasing width.

10. The method of forming eaves troughs, 115 which includes bending a sheet metal blank into trough shape by a series of successive operations in which it is initially acted upon along its median line by a male die having a narrow blank-engaging surface and is then gradually developed by a succession of sets of cooperating male and female dies in which the male dies have arcuately curved blank-engaging surfaces and succeeding male dies have said surfaces produced on 120 radii of progressively increasing length. 125

11. The method of forming eaves troughs, which includes an initial bending of a sheet metal blank into a shallow V-shaped channel form and then gradually developing a 130

trough shape by a succession of operations in which the depth of the channel is progressively increased and the walls of the blank at opposite sides of the angle produced by the initial bending are simultaneously developed into arcuate form by a succession of curving steps in which they are acted upon in areas which progressively widen from said angle outward toward the edges 10 of the blank.

12. The method of forming sheet metal

products of arcuately curved cross-section, which includes bending a sheet metal blank into trough shape by a series of successive curving operations in which it is developed 15 outward in opposite lateral directions in areas of relatively increasing width and in which areas lateral to that acted upon are unconfined.

In testimony whereof I affix my signature. 20

MARTIN L. HUNKER.
